UNITED STATES PATENT OFFICE.

RALPH J. PATTERSON, OF WATERTOWN, MASSACHUSETTS, ASSIGNOR TO WALKER & PRATT MANUFACTURING COMPANY, OF BOSTON, MASSACHUSETTS, A CORPORATION OF MASSACHUSETTS.

AUTOMATICALLY-CONTROLLED SWITCH DEVICE.

Application filed July 8, 1923. Serial No. 650,250.

This invention relates to automatically controlled electric switches, and possesses features of novelty and advantage which are particularly adapted for use in controlling, 5 through electrical means, devices such as electric heaters or ranges.

One object of the invention is to provide an improved form and arrangement of parts for an electrical switch to be controlled by 10 external conditions of temperature, pressure, changes in level of liquids, or the like, which is sensitive, accurate, and positive in operation in any position.

Another object of the invention is to provide an improved form of thermostatically 15 operated switch which cannot become injured by excessive movements of the thermostatic responsive means, due to extreme temperatures.

20 Another object of the invention is to provide an improved form of thermostatically controlled electric switch which may be easily adjusted to operate within any desired range of temperatures and which may be 25 quickly set so as to operate at any predetermined temperature within the selected range.

A further object is to provide a device of 30 this sort which is characterized by its extreme simplicity and compactness in construction, its sturdiness, and by its effectiveness in operation.

Other objects of the invention will be in 35 part obvious and in part pointed out hereinafter.

The invention accordingly consists in the features of construction, combination of elements and arrangement of parts which will be exemplified in the construction herein- 40 after set forth, and the scope of the application of which will be indicated in the appended claims.

In the drawings forming a part of the specification and in which similar reference 45 characters refer to similar parts,

Fig. 1 is an elevational view showing one form which the present invention may take;

Fig. 2 is a vertical sectional view there- 50 of; and

Fig. 3 is a view taken substantially on line 3-3 of Fig. 1.

Referring to the drawings in detail, my improved apparatus includes an electrical

switch having a casing or housing 9 within which is pivoted, as at 10, a switch arm 11 adapted for alternate engagement with the stationary terminals or contacts 12 and 13. These stationary contacts may be placed closely together so that the throw of the switch arm is very slight; that is to say, 55 when the switch arm is moved it leaves one contact and then engages the other one. These stationary contacts may be electrical- 60 ly connected to a solenoid operated switch, which controls the heating element of a 65 range for instance, in such manner that when the switch arm engages the upper contact 13, the remote switch is operated to throw the current onto the heating element of a range or oven, and the current through 70 the contact 13 is broken; and when the switch arm is thrown into engagement with the other contact 12, the remote switch is 75 opened to throw the heat "off" of the oven, and the circuit is broken through the contact 12. The movement of the switch arm 11 is controlled by suitable responsive de- 80 vice which is here shown as being in the form of a thermostat, as the features of the present invention are peculiarly adapted to 85 thermostatically control electric switches. This thermostat may comprise a metal tube 14 constructed of a material having a relatively high coefficient of expansion and a rod 15 therein of a material relatively non- 90 expansible with heat changes, for instance carbon. The tube 14 is closed at its lower end and is preferably threaded into a boss 16 depending from the housing 9 so that the 95 thermostat may be removed without disturbing the adjustment of the switch. When the tube 14 is heated, it is elongated so that the carbon rod is lowered, and when the tube cools off, it becomes shorter and raises the carbon rod. This thermostatic device controls movement of the switch arm 11 through a plunger 20 having at its lower end a head 21 which rests upon but is not connected to the top of the carbon rod 15. The plunger 100 is normally urged downwardly towards the rod 15 by a coiled spring 22 abutting at its opposite ends against the housing 9 and the head 21. The plunger has a sliding movement in the openings of the housing through which it passes and is held against 105 rotation by the splines or keys 23 operating

in the grooves 24. The switch arm is normally urged upwardly into engagement with the contact 13 by means of a suitable spring which, if desired, may take the form of a 5 leaf spring, such as designated by the numeral 25 in the drawings. It will be noted, particularly from Figs. 2 and 3, that the plunger has an elongated vertical slot or opening 26 through which the switch arm 10 11 extends.

Mounted for adjustment, for the purpose hereinafter described more in detail, within the upper end of the plunger 20 and extending down into the slot 26, is a threaded pin 15 or screw 27 which is adapted to bear against that side of the switch arm opposite to that of the spring 25, that is to say on the top of the switch arm. There is a considerable clearance 28 between the lower side of the 20 switch arm and the plunger so that the plunger will have no upward thrust against the switch arm and injure the mechanism when the tube 14 is foreshortened upon cooling off. Also, this clearance allows considerable lee-way in the matter of adjustment. The screw 27, which forms the only connection or engagement between the plunger and the switch arm, is preliminarily adjusted within the plunger to vary the effective 25 30 length thereof and thereby determine the range of temperatures within which the thermostatic device will actuate the switch. In order to set or regulate this pin longitudinally of the plunger within the selected range, so that the thermostatic device will 35 result in actuation of the switch at any desired predetermined temperature within that range, there is associated with this screw 27 what may be termed a regulating device 40 which is shown here in the form of a sleeve 30 having an indicating member in the form of a pointer 31 adapted to move over position indicating means, such as a scale 32, carried by the housing 9. In the present illustrative disclosure of the invention, the sleeve 30 is externally threaded and is screwed, for longitudinal adjustment, into the threaded recess 33 in the upper end of the plunger 20. The sleeve is internally threaded so as to 45 receive the pin 27, as shown most clearly in Figs. 2 and 3.

Preferably, the switch parts are carried by a stationary plate 35 of insulating material suitably secured to a housing. The contacts 12 and 13 are directly mounted on this 55 plate. The free end of the switch arm is insulated from the pivoted end by a connection 36 of insulating material. The free end of the switch arm is connected to a suitable 60 conductor 37. Connected respectively to the contacts 12 and 13 are the conductors 38 and 39 which may lead to suitable controlling mechanism, such as has been previously described.

65 The operation of the device will be readiiy

understood. The range of temperature within which it is desired that the device operate, having been selected depending on conditions, the pointer 31 will be set on the scale 32 to indicate a predetermined temperature within the selected range, and then the thermostatic device is heated up (as by placing it within a chamber, the temperature of which can be accurately controlled) to a temperature corresponding to that indicated 70 by the pointer 31 on the scale 32. The screw 27 will then be adjusted relatively to the sleeve 30 so that when the thermostatic device has been heated up to the predetermined temperature, the screw will engage 80 and throw the switch arm 11 downwardly to close the circuit through the lower contact 12. It will now be clear that, by so manually adjusting the screw 27 relative to the regulating means, including in part the pointer 31, the range of temperature within which the thermostat will actuate the switch arm is determined. To set the device so that the switch arm will be thrown at any desired predetermined temperature within the selected range, it is merely necessary to move the pointer 31 into registry with that indicating mark of the scale 32 which designates that predetermined temperature. In so moving the pointer 31, it is obvious that the 90 sleeve, together with the adjusting screw 27 carried thereby, will move up or down, as the case may be, within the plunger and thereby change the effective length or distance between the operative end of the screw 27 and the top of the thermostatic member 15.

The device, having been adjusted as just described, and, assuming that the screw 27 has been adjusted relative to the sleeve 30 so that the effective range of temperature is between 400 and 600 degrees, and that the pointer 31 has been set on the mark indicating 450 degrees, it will be seen that when the oven, for instance, to which the device is applied reaches a temperature of 450 degrees, the tube 14 will have been elongated to such an extent that the plunger is lowered to a point where the lower end of the adjusting screw 27 engages and depresses the switch arm 11, thereby throwing the same from engagement with the upper contact 13 into engagement with the lower contact 12. Assuming that the improved mechanism herein shown is used in combination with the heating element of an oven, the current on this heating element may be thrown off when the switch arm engages the contact 12 and, at the same time, the current through the switch arm and the contact 12 may be broken. Should the oven continue to heat up after the switch arm 11 has been thrown downwardly, as just described, no damage can result to the switch parts, for the head 21 of the plunger rests upon but is not connected 110 115 120 125 130

to the carbon rod 15, which means that the only downward force exerted on the plunger is that exerted by the spring 22. The pressure of this spring 22 will be such as not to injure or jam the device in any way. When the oven cools off, the tube 14 of the thermostatic device will contract and thereby raise the carbon rod 15, and when a temperature of approximately 450 degrees is reached, the plunger 20 will be raised to move the screw 27 out of engagement with the switch arm and then this switch arm, under the influence of the spring 25, will be thrown into engagement with the contact 13, and the controlling mechanism with which the switch is associated will throw the current onto the heating element. Should the temperature of the oven fall below 450 degrees, in which event the tube 14 would be further foreshortened, no injury or jamming of the switch would result because of the clearance 28 between the switch arm and the plunger. I have found, in actual practice, that the temperature of the oven may be controlled within very small limits, that is to say if the device is set to operate at 450 degrees, it will operate approximately at that temperature to throw the current off the heating element when the temperature of the oven rises, and will operate the switch arm 11 to throw the current onto the heating element when the temperature falls to 450 degrees.

From the foregoing description, it will be seen that my improved device is characterized by its extreme simplicity in construction and arrangement and, therefore, it may be manufactured at a relatively low cost while, at the same time, it is sufficiently strong and sturdy to withstand the duty placed upon it. It is particularly effective in operation in that it is extremely sensitive to changes in the responsive or actuating device, and it may be quickly and accurately set to operate at any desired temperature. The switch arm is thrown downwardly by the spring 22 and is thrown upwardly by the spring 25 so that at no time is there an excessive force exerted against the switch arm which means that the same will not be injured or jammed, and this is a matter of particular importance because the throw of the switch arm from one contact to the other is very slight. The movable switch member or part thereof, in the present instance the switch arm 11, passes through an opening in the plunger immediately beneath the adjusting screw 27 which makes for simplicity, and gives a direct thrust on the switch arm so that there is no tendency for the parts to cant or be thrown out of alignment. The device may be set by turning the screw 27 within the sleeve 30 so as to operate within any desired range, and the setting of the device so as to operate at any one predetermined temperature within the selected range

may be readily made by merely bringing the pointer 31 into proper position relative to the scale 32.

I claim as my invention:

1. In an apparatus of the character described, an electrical switch having a pair of contacts and a pivoted member between said contacts adapted to move from engagement with one into engagement with the other thereof; actuating means for said member including an element movable towards and away from said pivoted member, a connection between said pivoted member and element including a plunger movable relative to said member and element and engaging said member on the side opposite said element, said plunger being positively moved by said element only when the latter moves towards said pivoted member, said plunger being movable out of engagement with said member when the latter engages one of said contacts and said element has moved said plunger to a predetermined extent, said plunger being supported on said member free of said element when said member engages the other of said contacts, and a spring normally urging said pivoted member in the direction in which said plunger is positively moved by said element.

2. In an apparatus of the character described, an electrical switch having a pair of contacts and a pivoted member therebetween movable from engagement with one of said contacts into engagement with the other; actuating means for said member including an element movable towards and away from said pivoted member, a connection between said pivoted member and element including a plunger movable relative to said member and element, an adjustable part on said plunger engaging said member on the side opposite said element, said plunger being positively moved out of engagement with said element when said element has moved said plunger to a predetermined extent where said member engages one of said contacts, said plunger being supported free of said element by said member when the latter engages the other of said contacts, and a spring normally urging said pivoted member in the direction in which said plunger is positively moved by said element.

3. In an apparatus of the character described, an electrical switch having a pivoted member, a temperature responsive device including a part having a relatively high coefficient of expansion and a rod having a relatively low coefficient of expansion, a plunger loose of but engaging said rod, means adjustably carried by said plunger and engaging said member on the side opposite said rod, and a spring normally urging said plunger into engagement with said rod.

4. In an apparatus of the character de-

- scribed, a circuit controlling switch having a pair of slightly spaced apart contacts and circuit closing means including an arm; a thermostatic device including a part having a relatively high co-efficient of expansion and a rod having a relatively low co-efficient of expansion; a plunger having its inner end engaging but loose of said rod and having at its intermediate portion an opening through which said arm extends; and an adjustable screw in the outer end of said plunger engaging said arm on that side opposite to said thermostatic device.
5. In an apparatus of the character described, a circuit controlling switch including a pivoted arm, a change responsive device, a plunger constituting a connection between said arm and device, a member on the outer end of said plunger and engaging said arm on that side opposite to said device, said member being longitudinally adjustable on said plunger to determine the range of temperature within which said apparatus may operate, and temperature indicating mechanism including a part adjustable with respect to said member and adapted to adjust the same to any desired temperature within the selected range.
6. In an apparatus of the character described, a switch including a pair of slightly spaced apart contact members and circuit closing means adapted to move between said contacts and including an arm; a thermostatic device; a plunger constituting a connection between said device and arm and including a screw engaging said arm; and temperature indicating means including a part angularly adjustable with respect to said screw and adapted to turn and thereby set the same.
7. In an apparatus of the character described, a switch including a pivoted member, a change responsive device, a connection therebetween, a rotatable screw for varying the effective length of said connection to determine the range of operation, a temperature indicating mechanism for setting said screw to any desired point within the selected range and including a scale element and an indicating element, said rotatable screw being adjustable with respect to one of said elements to determine the range of operation and being rotatable with said element when the latter is rotated to set the device to operate at a given point in the selected range.
8. In an apparatus of the character described, an electrical switch having a pivoted member, actuating means therefor including an element movable towards and away from said pivoted member, a connection between said pivoted member and element including a plunger movable relative to said member and element, an adjustable part on said plunger engaging said member on the side opposite said element, said plunger being positively moved out of engagement with said member when said element has moved said plunger to a predetermined extent, a spring normally urging said pivoted member in the direction in which said plunger is positively moved by said element, and temperature indicating mechanism for adjusting said part and including a scale element and an indicating element, one of which elements is adjustably connected to said adjustable part for the purpose described.
9. In an apparatus of the character described, a circuit controlling switch arm normally urged into one circuit making position, a thermostat, a spring pressed member operatively associated with said thermostat and adapted to move said arm to another circuit making position, said member being provided with an adjustable screw to contact with said arm, a sleeve supporting said screw and threaded into said member, and means for rotating said sleeve.
10. In an apparatus of the character described, a base or housing, a switch theron having an arm, a spring normally urging said arm into one circuit controlling position, a plunger operatively associated with said switch arm, a thermostat, a second spring adapted to press said plunger into contact with said thermostat, a rotatable threaded sleeve in said plunger, a screw carried by said sleeve and adapted to press against said switch arm in a direction against the force of the first said spring, a scale on said base, and a lever carried by said sleeve and movable over said scale.

RALPH J. PATTERSON.
